UNITED STATES PATENT OFFICE.

WILLIAM TURTON, OF EAST ORANGE, NEW JERSEY.

DESIGN FOR A BAG-FRAME MEMBER OR SIMILAR ARTICLE.

55,402.

Specification for Design.

Patented June 1, 1920.

Application filed November 7, 1919. Serial No. 336,482. Term of patent 3½ years.

To all whom it may concern:

Be it known that I, WILLIAM TURTON, a subject of the King of Great Britain, residing at East Orange, county of Essex, and State of New Jersey, have invented a new, original, and ornamental Design for a Bag-Frame Member or Similar Article, of which the following is a specification, reference being had to the accompanying drawing, forming part thereof.

Figure 1 is a face view, and

Fig. 2 is an edge view of the new and ornamental bag frame member or similar article.

I claim:

The ornamental design for a bag frame member or similar article, as shown.

WILLIAM TURTON.
